UNITED STATES PATENT OFFICE.

HERBERT D. CHALLIS, OF PITTSBURGH, AND SAMUEL J. WILLIAMSON, OF SEWICKLEY, PENNSYLVANIA.

GOLF CLUB.

Application filed April 12, 1921. Serial No. 460,686.

To all whom it may concern:

Be it known that we, HERBERT D. CHALLIS, residing at Pittsburgh, in the county of Allegheny and State of Pennsylvania, and 5 SAMUEL J. WILLIAMSON, residing at Sewickley, in the county of Allegheny and State of Pennsylvania, both citizens of the United States, have invented or discovered certain new and useful Improvements in Golf Clubs, 10 of which improvements the following is a specification.

Our invention relates to improvements in golf clubs, and consists, in a word, of a golf club with a glass head. The invention 15 is primarily intended to apply to putters, but manifestly is applicable to other clubs as well.

Fig. I of the accompanying drawings is a view in medial longitudinal section of the 20 head of a golf club of our invention with the adjacent portion of the shank of the club secured thereto; Fig. II is a view of the same head portion of the club in end elevation; Fig. III is a view in plan from 25 above; and Fig. IV is a view in side elevation looking directly at the impact face.

The head 1 of the club is made wholly of 30 glass. In proportions and in size it is such as to afford the proper weight and proper disposition of impact face. Being formed wholly of glass the high resilience of the material becomes available and valuable, as is not the case with a club whose head is 35 composite of several materials of which only the impact face is of glass. The head of our invention is made transparent over its upper surface and opaque or translucent over its sole or lower face, and across the sole is scored or otherwise formed a sight line 2.

40 The impact face 3, which will be inclined 3° more or less from the vertical, may be scored by etched lines or otherwise, as indicated in Fig. IV.

The head may be secured to the shank of 45 the club by means of a collar or ferrule 4 formed conveniently of metal—aluminum, for example—bolted to and extending at proper angle from the upper face of the glass head. An adequate bolt structure is 50 indicated in the drawings. Into an upwardly tapering vertical opening 5 through the head is introduced a correspondingly shaped follower block 6. This block is provided with suitably arranged pins 7 extend-

ing vertically when the block is in place 55 from its upper surface and entering corresponding recesses in ferrule. These pins serve to prevent the head from turning from its position on the shaft when the club is assembled. A set screw 8 with head or 60 washer 9 rabbeted into the head of the club from beneath bolts ferrule 4 to head 1, binding follower block 5 in its tapered recess, with pins 7 in engagement with the recesses formed in ferrule 4 to receive them. The 65 end of the wooden shank 10 of the club is seated in the bore 11 of ferrule 4 and may be suitably secured there, as by the pin 12.

The advantages of the club, are primarily that consequent upon the high elasticity of 70 glass; we find by experiment that the compressed rubber ball "gets away" more rapidly from the face of the club when the stroke is made, and travels under a larger fraction of the force of the blow, than is 75 true in the use of clubs of usual materials. The sight line, viewed through the transparent head, is an aid to the player. In case of breakage of the glass head (it is not easily broken, and ordinarily will be carried 80 apart from metal-headed clubs), it is readily replaceable with another. Ordinarily a supply of glass heads will be ready in the hands of a "professional" or greens keeper to be bolted to the shanks of clubs. The 85 momentum of the head as a unit, unbroken by any yielding of component part against part, is concentrated in impact upon the ball. Excepting only metal clubs (compared with which the elasticity of glass is 90 high), all golf clubs in use have compound heads, in which an appreciable fraction of the momentum is lost in the yielding of component part against part.

We claim as our invention:

1. In a golf club structure, the combination of a head having a vertical upwardly tapered opening through it, a shank-receiving ferrule applicable to the upper surface of the head, a block of corresponding shape 100 with the said tapered opening through the head adapted to be introduced into the tapered opening in the head and being introduced to interlock with said ferrule, and a bolt member adapted to unite ferrule with 105 head and to secure said block in position in said opening.

2. In a golf club structure the combina-

tion of a head formed integrally of a block of glass and having a vertical upwardly tapered opening through it, a shank-receiving ferrule applicable to the upper surface of the head, a follower block adapted to be introduced from beneath into the tapered opening in the head, said ferrule and block being provided with inter-engaging means, and a bolt member adapted to unite ferrule

with head and to bring said block into position in said recess.

In testimony whereof we have hereunto set our hands.

HERBERT D. CHALLIS.
SAMUEL J. WILLIAMSON.
